WASYL KUC, OF WINNIPEG, MANITOBA, CANADA, ASSIGNOR OF ONE-HALF TO JACK ZUROWSKY, OF FISHER BRANCH, MANITOBA, CANADA.

PADLOCK.

1,398,380.

Specification of Letters Patent. Patented Nov. 29, 1921.

Application filed January 19, 1920. Serial No. 352,418.

To all whom it may concern:

Be it known that I, WASYL KUC, a citizen of Ukraine, residing at Winnipeg, in the Province of Manitoba and Dominion of Canada, have invented certain new and useful Improvements in Padlocks, of which the following is a specification.

The present invention relates to certain new and useful improvements in padlocks wherein a tensioned sliding bolt within the casing is adapted for engagement with the keeper end of a shackle pivoted to the casing, a key device being employed in shifting the sliding bolt against the tension of the spring for releasing the shackle keeper to permit the release of the shackle.

A further object of the invention is to provide a padlock embodying a hinged shackle and a tensioned sliding bolt with a screw carried by the bolt and adapted to be shifted within the lock casing to move the same to engaging and disengaging positions relative to the shackle keeper.

With the above and other objects in view, the invention consists in the novel form, combination and arrangement of parts herein fully described and shown in the accompanying drawing, wherein like reference characters indicate similar parts throughout the several views.

In the drawing,

Figure 1 is a side elevational view of a padlock constructed in accordance with the present invention,

Fig. 2 is an end elevational view of the lock,

Fig. 3 is an end elevational view taken from the opposite end of the lock,

Fig. 4 is a vertical longitudinal sectional view of the lock showing the tensioned sliding bolt with the bolt in locked position,

Fig. 5 is a sectional view similar to Fig. 4 showing the sliding bolt retracted with the shackle removed from the casing,

Fig. 6 includes side and end elevational views of the sliding bolt removed from the casing and

Fig. 7 is a side elevational view of the key for the lock.

Briefly described, the present invention aims to provide a padlock wherein a pivoted shackle has the keeper end thereof securely locked within a casing with a special form of key coöoperating with the sliding

bolt in the lock for shifting the bolt to disengaging position relative to the shackle keeper. The lock embodies from a structural standpoint the casing having a shackle pivoted thereto with a tensioned bolt slideable within the casing and adapted for engagement with the keeper end of the shackle. A screw forms a part of the sliding bolt and is adapted to be engaged by a threaded key for shifting the bolt within the casing to free the same from an engagement with the shackle keeper.

Referring more in detail to the accompanying drawing, there is illustrated a padlock embodying a casing 8 having an enlarged end 8' defining an annular shoulder 8" carrying spaced lugs 9 between which a shackle 10 is pivoted upon the pin 11, the casing 8 having a side opening 12 adjacent the closed end 13 thereof through which the keeper 10' of the shackle is adapted to be projected. The inner edge wall of the shackle 10 is provided with a shoulder 10^a and an offset portion 10^b so that the shackle in effect, interlocks with the casing by the engaging shoulders 8" and 10^a as shown in Figs. 1 and 2. This construction removes considerable strain from the shackle pivot 11 when the shackle is subjected to end thrusts.

The sliding bolt for retaining the shackle keeper 10' within the casing 8 embodies a disk portion 14 insertible within the open end of the casing as shown in Figs. 4 and 5 while the pin 15 carried by the forward face of the bolt body 14 is adapted to be projected through the opening 16 in the partition 17 extending transversely of the casing, the opening 16 being arranged adjacent the casing opening 8 as shown in said figures. The rear face of the bolt body 14 carries a screw 18 by which said bolt is shifted within the casing. After positioning the bolt within the casing, the compression coil spring 19 is placed therein to surround the screw 18 of the sliding bolt, the inner end of the spring engaging the rear face of the bolt body 14 while said spring at its rear end is engaged by the ring 20 that is sweated or otherwise secured in the open enlarged end 8' of the casing.

With the construction above described, assuming that the shackle keeper 10' is within the casing 8 as shown in Fig. 4, the spring 19 forces the bolt body forwardly

into engagement with the casing partition 17 for projecting the bolt pin 15 through the partition opening 16 and into the shackle keeper 10'. The shackle keeper thus positioned, is securely maintained in locked arrangement, and in order to release the shackle from the casing, the form of key 21 shown in Figs. 5 and 7 is employed. The key 21 has a shoulder portion 22 carrying a handle 23 while the body portion 14 thereof is of tubular construction and internally threaded as at 24. The key 21 is inserted within the open end of the lock casing 8 for engagement with the screw 18 and by threading the key onto the screw, the shoulder 22 of the key will engage the enlarged end 8' of the casing and cause the screw 18 upon the sliding bolt 14 to be retracted into the tubular key 21 with the subsequent withdrawal of the bolt pin 15 from the shackle keeper 10'. With the bolt and bolt pin retracted, the shackle 10 may be moved upon its pivot pin 11 with the key 21 positioned within the casing. When it is desired to lock the shackle within the casing, the keeper 10' is moved within the opening 12 of the casing and a key reversely rotated to cause a forward projection of the bolt with the bolt pin 15 received in the shackle keeper 10'. Rotary movement of the bolt is prevented by the bolt pin 15 projecting through the partition opening

16. It will therefore be seen that the operation of this lock is extremely difficult unless one is provided with the exact key embodying the same pitch of threads as shown upon the screw 18 of the sliding bolt.

While there is herein shown and described the preferred embodiment of the invention, it is nevertheless to be understood that minor changes may be made in the form, combination and arrangement of parts without departing from the spirit and scope of the invention as hereinafter claimed.

What is claimed as new is:

A lock of the class described comprising a circular casing having an enlarged rear end defining a beveled annular shoulder, spaced lugs formed on and extending laterally from the enlarged rear end of said casing, a shackle having one end pivoted between said lugs with an inner edge thereof offset to provide a beveled shoulder for engagement with the beveled casing shoulder, compensating for strains when the shackle is subjected to end thrusts, a keeper portion upon the offset end of said shackle projecting into the casing, and a sliding bolt within the casing adapted to engage the shackle keeper.

In testimony whereof I affix my signature.

WASYL KUC.
